Attorney

UNITED STATES PATENT OFFICE.

CHARLES L. ALLEN, OF CLAREMONT, VIRGINIA.

POULTRY NEST.

Application filed June 27, 1923. Serial No. 648,039.

To all whom it may concern:

Be it known that I, CHARLES L. ALLEN, a citizen of the United States, residing at Claremont, in the county of Surry and 5 State of Virginia, have invented certain new and useful Improvements in Poultry Nests, of which the following is a specification, reference being had to the accompanying drawings.

10 This invention relates to improvements in poultry nests and more particularly to the provision of a metallic poultry nest.

An important object of the invention is 15 to provide a device of this character which is collapsible, permitting its ready shipment, and which may be produced at a very low cost.

A further object of the invention is to 20 provide a device of this character which is readily assembled and which when assembled is free, to the greatest possible extent, of crevices in which mites and lice can collect.

A further object of the invention is to 25 provide a device of this character which is readily installed and which is so constructed that a single nest of a row may be readily removed if so desired.

These and other objects I attain by the 30 construction shown in the accompanying drawings, wherein for the purpose of illustration is shown a preferred embodiment of my invention and wherein:—

Figure 1 is a vertical sectional view 35 through a poultry nest constructed in accordance with my invention;

Figure 2 is a similar view taken at right angles to the view in Figure 1; a similar nest being shown adjacent thereto in dotted 40 lines.

Figure 3 is a perspective view showing the main body section and the bottom section;

Figure 4 is a perspective view showing 45 the inner face of the front plate.

Figure 5 is a detail sectional view showing the manner of engagement of the top and bottom plates with the main body section; and

50 Figure 6 is an enlarged sectional view showing the manner of connecting the top and bottom sections to the front plate and main body section.

Referring now more particularly to the 55 drawings, the nest embodies a main body

section 10, which forms a back 11 and sides 12 of the nest and which is formed from a single sheet of metal bent to provide these three surfaces. The back 11 has formed therein approximately centrally thereof and adjacent the top and bottom edges pairs of spaced openings 13. The sides 12 approximately centrally thereof are provided with spaced slits 14 extending downwardly from the top edges and upwardly from the bottom edges and forming therebetween tabs 15, the purpose of which will hereinafter appear.

The front of the nest is formed by a plate 16, which is provided centrally with an entrance opening 17. This opening is formed 70 by severing a strip 18 of the material of the plate forming the front along its side and top edges and leaving the bottom edge attached to the plate. In use the detached section 18 is bent outwardly along its attached edge, then reverted, as indicated at 19 and the end portion 20 thereof bent downwardly so that it lies against the outer face of the plate from which the front 16 is formed with its lower edge coincident 80 with the lower edge of this plate. That portion of the detached section 18 between the point of attachment and the reverted portion 19 forms a ledge 27 upon which the hen may step in entering the nest. Imme- 85

diately above the upper edge of the opening 17 a series of transversely spaced openings 22 is formed, the purpose of which will hereinafter appear. Centrally of the plate 16 and adjacent the top and bottom edges 90 thereof pairs of spaced openings 23 are pro-

vided similar to the openings 13 of the rear wall 11 and the main body section. The vertical terminal portion 20 of the section 18, may, if so desired, be provided with open- 95

ings 24 aligning with the openings 23 of the lower edge of the front plate 16. The side edges of the front plate are provided with rearwardly directed flanges 25, these flanges being notched, as indicated at 26, at points 100

vertically spaced from the center of the flange to divide the flanges into three separate sections 27, 28 and 29. The flanges 27 and 29 are arranged in the same plane and the flanges 28 are arranged in a plane trans-

versely offset from the plane of the flanges 27 and 29 a distance such that the forward edges of the sides 12 may enter between these flanges to interlock therewith.

A top 30 and bottom 31 are provided, the 110

top and bottom being each provided about the side edges thereof with vertically disposed flanges 32 and at the front and rear edges thereof with vertically disposed flanges 33. The flanges 32 are adapted to receive and engage against the outer walls of the sides 12 of the main body section, the central portions of the flanges 32 extending through the slots 14 so that the tabs 15 are arranged upon the outer walls of the flanges 32. The flanges 33 are provided with pairs of transversely spaced openings 34 and 35 adapted for alignment with the openings 13 of the rear wall section 11 and the openings 23 of the front wall section 16, respectively. The bottom 31 has formed therein adjacent its forward edge a plurality of transversely spaced openings 36, corresponding in number and spacing to the openings 22 of the front plate 16.

In assembling the device the front plate 16 is applied to the forward edges of the side walls 12 of the main body section with flanges 27, 28 and 29 thereof interlocking 25 with the forward edges of these side walls, as hereinbefore described, thus completing the four side walls of the nest. The top and bottom of the nest are then applied, the flanges 32 interlocking with the side wall 30 tabs 15 of the side walls 12, as hereinbefore described. When the top and bottom are so applied the openings 34 and 35 of the flanges 33 thereof align with the openings 13 or 23, respectively, for the reception of securing 35 elements 37 these securing elements are preferably in the form of U-shaped wires the ends of the arms of which are directed through the openings and then bent, as at 38, to prevent their withdrawal. In assembling the device the edge of the lower edge of the vertical portion 20 of the section 18 is engaged between the forward flange 33 of the bottom 31 and the adjacent face of the front plate 16, so that it rests upon the 40 upper surface of the bottom to be supported thereby. The securing element 37 will be directed through the opening 24 of this vertical portion, if such openings are provided, and will when so employed effectually prevent any movement whatever of the section 18. Attention is directed to the fact that the reverted portion 19 of the section 18 being downwardly inclined and attached to and abutting against the front plate serves as a 45 bracing support for the ledge 21 to stiffen the same. This downward inclination further provides between the adjacent faces of the reverted portion and ledge a space 39 through which a connecting pole 40 may be directed. By the use of this pole the nest may be simply placed upon supports 41, the pole serving to maintain the nest against movement upon the supports and keeping the nests in alignment. When it is desired 50 to move a single nest, this may be readily

accomplished by withdrawing the pole and removing the nest desired. If it is desired to simultaneously remove all of the nests the pole is simply withdrawn, carrying with it all of the nests which may be readily removed from the poultry house for cleansing. Being of metal the nest may be subjected to fire or other desired treatment to remove filth or vermin without damage thereto.

It is pointed out that a nest of this character may be readily collapsed for shipment, will occupy but little space, is readily assembled, and may be manufactured at a very low cost. The nest is further capable of use as a setting nest or as a cage to segregate fowls by employing grate wires 42. These wires are straight with the exception of one end which has a hook 43 formed thereon introduced through the openings 22 of the plate 16 and their lower ends dropped through the openings 36 of the bottom plate 31. When in position they form a barrier for the entrance which will prevent either the entrance or exit of fowls and at the same time will in no manner interfere with the ventilation of the nest. It will, of course, be understood that the construction hereinbefore set forth is but a specific example of the construction of the poultry nest and is capable of a considerable range of change 55 and modification without materially departing from the spirit of my invention and I accordingly do not limit myself to such specific structure except as hereinafter claimed.

I claim:

1. In a nest of the type described, a front plate having a section of the size of the desired entrance opening separated therefrom along its side and upper edges, the section being bent outwardly from the plate along the attached edge thereof to form a ledge and at a point spaced from the plate being reverted and its end portion brought into engagement with the plate.

2. In a nest of the type described, a front plate having a section of the size of the desired entrance opening separated therefrom along its side and upper edges, the section being bent outwardly from the plate along the attached edge thereof to form a ledge and at a point spaced from the plate being reverted and its end portion brought into engagement with the plate and secured thereto.

3. In a nest of the type described, a body portion forming four enclosing walls and a top and bottom, one pair of opposed walls being provided at the upper and lower ends thereof with pairs of spaced vertically extending slits forming a tab, the top and bottom being each provided upon those edges thereof corresponding to said walls with vertically extending flanges engaged between the outer faces of said walls and the inner

faces of the tabs thereof, and means for attaching the remaining walls to the top and bottom.

4. In a nest of the type described, a body portion including a main section forming rear and side walls and a front wall, the front wall being provided along its vertical edges with a plurality of angular flanges, alternate flanges of the front wall being adapted to engage upon opposite sides of the side wall thereby to maintain the side walls in fixed relation to the front wall and the top and bottom members secured to the main section and front wall and preventing separation thereof.

5. In a nest of the type described, a body portion including a main section forming rear and side walls and a front wall, the front wall being provided along its vertical edges with a plurality of angular flanges, alternate flanges of the front wall being adapted to engage upon opposite sides of the side wall thereby to maintain the side walls in fixed relation to the front wall and the top and bottom members secured to the main section and front wall and preventing separation thereof, the side walls being vertically slit at their upper and lower edges to provide tabs, the top and bottom having vertically disposed flanges engaging the outer faces of the side walls and against which the inner faces of the tabs engage.

6. In a nest of the type described, a body portion including a main section forming rear and side walls and a front wall, the front wall being provided along its vertical edges with a plurality of angular flanges, alternate flanges of the front wall being adapted to engage upon opposite sides of the side wall thereby to maintain the side walls in fixed relation to the front wall and the top and bottom members secured to the main section and front wall and preventing separation thereof, the side walls being vertically slit at their upper and lower edges to provide tabs, the top and bottom having vertically disposed flanges engaging the outer faces of the side walls and against which the inner faces of the tabs engage,

and other vertical flanges engaging the front and rear walls and securing elements extending through the last named flanges and the associated walls to secure the same in fixed relation.

7. In a nest of the type described, a body portion including a main section forming rear and side walls and a front wall, the front wall being provided along its vertical edges with a plurality of angular flanges, alternate flanges of the front wall being adapted to engage upon opposite sides of the side wall thereby to maintain the side walls in fixed relation to the front wall and the top and bottom members secured to the main section and front wall and preventing separation thereof, the front wall having an entrance opening formed therein, a plurality of transversely spaced openings formed above the entrance opening, a plurality of openings formed in the bottom plate and aligned with the openings of the front plate, and wires directed through the first named openings and having their ends extending through the last named openings for forming a grate preventing passage through the opening of the front plate.

8. In a nest of the type described, a body portion including a main section forming rear and side walls and a front wall, the front wall being provided along its vertical edges with a plurality of angular flanges, alternate flanges of the front wall being adapted to engage upon opposite sides of the side wall thereby to maintain the side walls in fixed relation to the front wall and the top and bottom members secured to the main section and front wall and preventing separation thereof, the front plate having an opening therethrough, the metal removed in forming the opening being attached to the plate along its lower edge and being bent outwardly from the plate to form a ledge and subsequently bent inwardly and engaged with the plate to form a brace for the ledge.

In testimony whereof I hereunto affix my signature.

CHARLES L. ALLEN.
